Primary Examiner — Rashida Johnson

(74) Attorney, Agent, or Firm — Fross Zelnick Lehrman & Zissu, P.C.; Charles T. J. Weigell, Esq.

CLAIM

The ornamental design for a dress, as shown and described.

DESCRIPTION

The broken line depicting the outline of portions of the garment shows unclaimed subject matter.

1 Claim, 2 Drawing Sheets
